BOOKMARK

Edwin A. Myers, Long Beach, Calif., assignor of
one-half to Harrison G. McDonald, Pasadena,
Calif.

Application October 12, 1951, Serial No. 251,027

3 Claims. (Cl. 116—119)

1

The present invention relates to improvements in a bookmark. It consists of the combinations, constructions, and arrangement of parts, as hereinafter described and claimed.

Among the various objects of this invention, I propose to provide a bookmark, which includes a holder adapted to be interengaged readily with the last index page, fly-leaf, or other selected page of a book or the like, so as to be supported thereby. This holder serves as a mounting for a resilient strip-like marker, which is provided with a free resilient extension adapted to overlie a page of the book so as to provide a mark therefor. Upon turning the designated page, the marker strip will yield and slip over the marginal edge of that page, and come to rest on a subsequent page. In this manner, the successive pages of the book will be marked as they are turned by the reader, thus indicating at all times the reader's place in the book.

More particularly described, I make use of a resilient strip-like marker having a portion thereof defining a complete loop. The convolution of this loop is slidably attached to the holder. One end of this strip extends from the loop so as to provide a free extension adapted to overlie a page of the book to serve as a page-designator. Of course, when reader commences the book, this extension must project to a greater extent relative to the rear fly-leaf in order to overlie the initial pages than will be the case when the reader reaches pages toward the back of the book. The looped portion will furnish the necessary length for the extension so that the latter may be pulled downwardly over the page being read to the proper distance, and still accommodate the thickness of the unread part of the book.

As a still further object, I provide a bookmark of the character described, which is attractive in appearance, easily applied to the book, simple and durable for the purpose intended. Moreover, the marker will not mar or deface the pages, or interfere with the reading of the book. The reader's place cannot be lost, even if the book falls, is held upside down, or closed accidentally. Of course, I do not wish to be limited to any particular class or type of book to which my device may be applied.

Other objects and advantages will appear as the specification continues. The novel features will be set forth in the claims hereunto appended.

Drawings

For a better understanding of my invention, reference should be had to the accompanying

2

drawing, forming part of this application, in which:

Figure 1 is a perspective view of my bookmark by itself;

5 Figure 2 is a vertical sectional view taken along the plane II—II of Figure 1, disclosing the rear fly-leaf and adjacent cover of a book by dot-dash lines;

Figure 3 is a vertical transverse sectional view 10 taken through a closed book, illustrating my bookmark applied thereto;

Figures 4 and 5 are development face views of 15 my holder and marker strip, respectively.

While I have shown only the preferred form 20 of my invention, it should be understood that various changes, or modifications, may be made within the scope of the annexed claims without departing from the spirit thereof.

Detailed description

25 Referring to the drawing in detail, I have shown the complete bookmark in Figure 1. It includes a holder designated generally at A, and a strip-like marker B. The holder may be fashioned from any suitable material that will not mar or damage pages of a book when engaged therewith. Leather or plastic may be utilized for this holder, but I do not desire to be limited in this regard. The strip marker is made from 30 resilient transparent material, such as cellophane.

In its structural features, the holder A is folded back upon itself, as at 10, to present front and rear flaps 11 and 12, respectively. Thus, a substantially U-shaped structure is provided, which is adapted to be telescoped or engaged over a rear fly-leaf 14, last index page, or other selected page of a book C (see Figure 3), so as to be supported thereby.

35 40 As clearly shown in Figures 2 and 4, the holder is pierced by a pair of parallel slots 15 and 16, which are disposed adjacent to the fold 10. For enhancing the general appearance of the holder, and at the same time make the holder more flexible in the region of this fold, I have provided recesses 17 in opposing lateral edges thereof. The particular shape or curvature of these recesses may be changed.

The marker strip B has its end 18 turned upwardly along the bend-line 19 so as to extend at an angle relative to the general length of the strip. Cellophane, of course, may be preshaped for this purpose. The other end 20 of this strip may be pointed.

45 50 55 In applying the strip B to the holder A, the

pointed end 20 of the strip is inserted through the slots 15 and 16, in order, and the strip pulled until the upturned end 18 is drawn against the fold 10 of the holder. Thereafter, the intermediate portion of the strip is fashioned into a loop 21 and the point 20 is passed through the slots 15 and 16 again. Thus the convolution of the loop overlaps itself, and the loop is slidably attached to the holder. The projecting section 22 of the strip provides a free extension extending from the loop, which is adapted to overlie a page of the book C to serve as a page-designator. The end 13 of the strip is confined in the interior of the loop.

For the purpose of illustration, the book has been shown as including front and rear covers 23 and 24, respectively, having a plurality of pages 25 disposed therebetween. The free extension 22 may be placed over any selected page in the book so as to designate the reader's place. Inasmuch as the marker strip is resilient, it will yield as each page is turned, and thereafter will rebound into a position overlying the subsequent page.

Quite naturally, when the holder A is applied initially to the rear fly-leaf 14 of the book, the extension 22 may be pulled downwardly, constricting the size of the loop 21, and thus providing the necessary length for the strip to overlie the first page of the book. As the pages are turned in succession, the total thickness of the remaining unturned pages will decrease, and thus part of the projecting section 22 may be drawn back into the loop.

As clearly shown in Figure 3 the looped portion of the strip is disposed to one side of the holder A, and on that side thereof having the slotted front flap 11. This will present the loop 21 between the planes of the front and rear covers of the book so that either of these covers may be placed flatwise on a table, or the like, without interference by the loop.

Inasmuch as the marker strip is transparent, it will not hinder the reader's vision of the subject matter contained on the pages of the book.

Summary

Having thus described the various parts of my bookmark, the purpose and use thereof are summarized briefly as follows:

1. The holder A of the bookmark is applied to the rear fly-leaf 14, or last index page, of any book, or magazine. It constitutes a definite improvement over other markers applied to the back of the books. Another improvement is that no interference will result when the holder is applied to the last index page.

2. The bookmark is automatic, as it flips through the pages as they are turned, and its transparent pointer section 22 makes reading through it possible, when it is disposed at the top of the pages.

3. The material used, such as leather or plastic for the holder A, and cellophane for the marker B, cannot harm the books or magazines, and never interferes during reading.

4. The reader's place cannot be lost, even if the book falls, or is held upside down, or if the book closes when one falls asleep while reading in bed.

5. The bookmark is useful in keeping the place wherever pages are turned, such as: law book reference, music sheets, bibles, technical

70

books, office ledgers and books of accounts, marking the place of Federal Code books for the Army, Navy and Air Force. Several of the bookmarks may be applied to pages directly to serve as reference guides, which also applies to law books for law case references. Also, it protects the place when drawing off trial balances from ledgers, and aids in giving telephone quotations from price books, if interruption causes the book to close. The place cannot be lost.

It will be noted that only two parts are used for my bookmark; namely: the holder A and the marker strip B. No metal is required. The cellophane strip or pointer is replaceable without removing any other parts.

I claim:

1. In a bookmark of the character described: a holder adapted to be interengaged with a fly-leaf, or other selected page, of a book, so as to be supported thereby; and a resilient marker strip having a portion thereof defining a complete loop; the convolution of this loop presenting overlapped sections, both of which are slidably attached to the holder; one end section of the strip providing a free extension projecting from the loop adapted to overlie a page of the book to serve as a page-designator; the other end of the strip being upturned to form an abutment positioned and confined within the interior of the loop to abut the holder, and thereby preclude this end from being pulled out of the holder when pull is exerted upon the page-designator end of the strip.

2. In a bookmark of the character described: a holder including a piece of material folded upon itself to present a pair of flaps adapted to straddle a fly-leaf, or other selected page, of a book, so as to be supported thereby; the holder being pierced by a pair of slots disposed adjacent to the fold thereof; and a resilient marker strip rolled upon itself to define a complete loop; the convolution of this loop presenting overlapped sections, both of which slidably extend through both slots of the holder; one end section of the strip providing a free extension projecting from the loop adapted to overlie a page of the book to serve as a page-designator; the other end of the strip being upturned to form an abutment arranged to bear against the holder and preclude this end from being pulled through the slots when pull is exerted upon the page-designator end of the strip.

3. The combination as defined in claim 2, in which one of the slots is arranged in the fold of the holder, and the other slot is fashioned in a flap of the holder; the loop being disposed on and confined to that side of the holder having the slotted flap.

EDWIN A. MYERS.
